Specification of Letters Patent.

Patented Dec. 2, 1919.

Application filed April 15, 1915. Serial No. 21,580.

To all whom it may concern:

Be it known that I, JOSEPH N. GILBERT, a citizen of the United States, residing at #2614 Grand avenue, Minneapolis, in the 5 county of Hennepin and State of Minnesota, have invented new and useful Improvements in Electromagnetism, of which the following is a specification.

This invention relates to the production 10 of magnetism from alternation current. The object of the invention is to produce magnetism which shall be unequal for the alternations of opposite sign, which inequality may be carried to the extent that the magnetism of one sign or polarity only may 15 be produced by alternating currents. The application for generating and transmitting electrical energy, filed June 5th, 1914, Serial No. 843,217, covers broadly the production 20 of unequal amounts of magnetism corresponding to the alternations of opposite polarity of an alternating current, which may be carried to the extent that the magnetism may be limited to one sign only, by causing 25 the magnetic energy applied to the magnetic circuit in which the magnetism is produced, during successive half cycles of different sign of the alternating current, to be unbalanced. According to the present invention, 30 this result is attained by supplying a balanced magnetizing energy, such for instance as the ordinary alternating current of sine wave form, to a coil or primary on the core to be magnetizing and unbalancing 35 the action of a secondary coil on said core for successive alternations of opposite sign.

Other and ancillary objects of the invention will appear hereinafter.

In the accompanying drawings which 40 illustrate the invention;

Figure 1 is a diagram showing electrical apparatus and connections embodying the invention;

Figs. 2, 3, 4 and 5 are magnetization 45 curves, in which positive magnetizing force is indicated by distance to the right of line B and negative magnetizing force by distance to the left of line B, while positive flux is shown by the distance above line H and negative flux by the distance below line H;

Figs. 6 and 7 are curves showing electromotive force plotted in the usual manner,

namely, by having abscissas represent time and ordinates the electromotive force. 55

Fig. 8 is a diagram showing a modified form of apparatus and connections;

Fig. 9 is a diagram showing a further modification of apparatus and connections;

Fig. 10 is a diagram showing a further 60 modification;

Fig. 11 is a diagram showing a particular mounting of unbalancing resistance;

Fig. 12 is a fragmentary view showing on an enlarged scale developed slip ring 65 segments with unbalancing resistance connected thereto.

Referring to the drawings and first more particularly to Fig. 1, an inductor generator has its field coils 2 and 3 excited by means 70 of a direct current generator 1 acting as an exciter. The coils 2 and 3 are mounted upon the yoke 4 having poles 5 and 6. The coil 2 is connected with the generator by conductors 62 and 63, a switch 66 serving 75 to control the circuit of this coil. The coil 3 is connected with the exciter by means of conductors 64 and 65, its circuit being controlled by the switch 67. The coils 2 and 3 are oppositely wound so that they tend to 80 force flux in opposite directions about the ring 4 so that the poles 5 and 6 are consequent poles. Wound upon the poles 5 and 6 are coils 7 and 8 in which electromotive force is induced as the inductor 12 rotates 85 between the pole pieces 5 and 6. These coils are shown as so wound and connected in series that their electromotive forces are added so that the difference of potential at the terminals 9 and 10 is equal to the sum 90 of the electromotive forces generated in the coils 7 and 8. The inductor 12 is keyed to the rotating shaft 11 so that as the shaft is rotated the inductor will rotate between the poles 5 and 6 thereby varying the magnetism traversing the coils 7 and 8 and causing a corresponding induction of electromotive force in those coils. 95

Coil sections 23 and 24 constituting a primary winding on the magnetic core 25, 100 are connected across the terminals 9 and 10 of the generator by means of conductors 52 and 57, this circuit being controlled by means of the switch 46. The core 25 is shown as of a horse-shoe shape having poles 105 26 and 27 and has its circuit closed through

a magnetic block 30 which is mounted on studs 28 and 29 of non-magnetic material and is spaced from the member 25 by means of non-magnetic washers 33 and 34. Also 5 mounted upon the core 25 are coils 31 and 32 connected in series and forming a secondary winding. Connected with one terminal of the secondary winding through a switch 45 for controlling the secondary circuit, is a non-inductive resistance 39 from which the circuit leads through the variable resistance 40 to the other terminal of the secondary winding. Provision is made for periodically short circuiting the resistance 40 as follows: 10 15 The conductor 61 leads from one terminal of the resistance 40, through the switch blade 47, sliding contact 50, stationary contact 49 and conductor 54 to the brush 20, bearing successively upon collector ring segments 14, 16, 13 and 15, which turn with the generator shaft 11. The other terminal of the resistance 40 is connected by a switch 51 and the conductor 53 with a brush 21 bearing upon the continuous collector ring 25 30 35 40 45 50 55 60 65 70 75 80 85 90 95 100 105 110 115 120 125 130 19 which also turns with the shaft 11. The segments 15 and 16 are connected by conductors 17 and 18 of low resistance with the ring 19 so that when the brush 20 bears upon either the segment 15 or the segment 16, the conductors 53 and 54 will be connected together and form a short circuiting shunt about the resistance 40 so that this resistance will be removed from the circuit of the secondary above referred to. There is provided a brush 22 which is also adapted to bear on the segments 16, 13, 15 and 14, which is connected by a conductor 55 with the switch contact 48, so that when the switch arm 47 is thrown from the contact 49 to the contact 48, the brush 22, instead of the brush 20, will be connected with one terminal of the resistance 40. Under these circumstances, the short circuiting of the resistance 40 will occur at different angular positions of the generator rotor, and consequently at different parts of the cycle of the generator electromotive force. As will be hereinafter more particularly referred to, the resistance 40 may be so inserted as to cause either the positive or negative magnetism in the core 25 to preponderate, and the shifting from one polarity to the other may be accomplished by moving the switch arm 47 from engagement with the contact 58 to engagement with the contact 49 or vice versa, thereby connecting either the brush 20 or 22 as may be desirable according to the preponderating polarity of magnetism wanted. 60 Connected in parallel with the primary 23 and 24 across the generator terminals 9 and 10, is a primary coil 35 which has one terminal connected through the switch 44 and the conductor 58 with the conductor 56 leading 65 to the terminal 10, while the other terminal of the coil is connected through the conductor 60 with the conductor 52 leading to the terminal 9. The primary coil 35 is mounted upon a magnetic core 36 having its circuit closed through a magnetic block 30, 70 but a gap is formed in the magnetic circuit by means of non-magnetic washers 33 and 34 mounted on the non-magnetic studs 28 and 29 upon which the yoke or block 30 is secured in position. Upon this magnetic 75 80 85 90 95 100 105 110 115 120 125 130 core are wound the secondary coils 37 and 38 having their circuit closed through the switch 43, the non-inductive resistance 41 and the variable resistance 42. The terminals of the resistance 42 are connected one through the conductor 59 with the conductor 53 and thence to the brush 21, while the other is connected with the brush 22 through the conductor 55 so that this resistance is short circuited whenever the segment on 14 which the brush 22 bears is connected with the brush 21 through one of the low resistance connections 17 or 18 and the ring 19. In explanation of the operations which take place, if a source of alternating electromotive force giving a curve of the general form as shown in Figs. 6 or 7, be connected to the terminals of a reactance coil, such as a transformer primary, the transformer will have, after a succession of cycles, an alternating magnetic flux in its core of equal positive and magnetic polarity, giving a curve of the general form shown in Fig. 4. The positive half cycle or alternation of impressed electromotive force as indicated by the curve E—F—G of Figs. 6 or 7 is opposed by a reactive electromotive force induced in the coil by the negative flux decreasing from maximum to zero (S to U Fig. 4) and by the positive flux increasing from zero to maximum (U to P). The negative half cycle or alternation of impressed electromotive force, is opposed by a reactive electromotive force induced by the positive flux decreasing from maximum to zero (P to R) and the negative flux increasing from zero to maximum (R to S). Hence each alternation of the applied electromotive force is opposed by a reactive electromotive force induced by a flux variation equal to the sum of the maximum values of the positive and negative fluxes. However, during the first few cycles, the transformer flux may alternate with unequal magnetic polarity, the degree of inequality depending upon the instant of the electromotive force cycle that the switch is closed connecting the transformer primary to the source of electromotive force. If the switch be closed at the beginning of the positive alternation of the electromotive force (Figs. 6 or 7), then the entire first half cycle of the applied electromotive force is opposed by a reactive electromotive force induced by the increase of the positive flux only. There-

fore, depending upon the nearness of the transformer core to saturation, the maximum flux P of the first cycle (Fig. 2) may be nearly twice as great as the maximum 5 positive flux P (Fig. 4), where the magnetization curve is symmetrical. With each successive cycle, however, there is an inherent tendency decreasing the maximum positive flux and increasing the maximum 10 negative flux until the flux alternates with equal positive and negative values.

There will now be explained the cause of this tendency of the magnetization curve to assume a symmetrical form and the means 15 for counteracting this tendency so as to cause the flux to alternate with any degree of inequality between the maximum positive and negative values, or to be a flux of one magnetic polarity only, the former as shown 20 as for instance in Fig. 3, and the latter as shown in Fig. 2. This will be explained in connection with the apparatus of Fig. 1.

In Fig. 1 with an exciting current supplied by the exciter 1 to the exciting coils 2 25 and 3 so as to produce consequent poles at the poles 5 and 6, and with the switches 43, 44, 45 and 51 open (that is with the secondary circuit of the transformer having the core 25 open and with connections to the 30 primary on the core 36 open so that current is supplied by the generator to the primary on the core 25), if the generator inductor 12 be rotated from its horizontal position in a clockwise direction, the variation of the reluctance of the magnetic circuit, will cause a 35 variation of the flux through the induced coils 7 and 8. This will induce an alternating electromotive force in the coils 7 and 8, which will be impressed upon the terminals 40 9 and 10, and alternating currents will flow through the circuit through the primary winding on the core 25 and, as previously referred to, after a succession of cycles of 45 alternating current, the flux in the core 25 will be symmetrical as represented by the magnetization curve of Fig. 4. The path of the current through the primary circuit just referred to, is from the terminal 9 through the conductor 52, coils 23 and 24, 50 switch 46, conductor 57 and conductor 56 to the terminal 10.

To simplify the explanation, let it be assumed that the number of turns in the coils 7 and 8 is equal to the number of turns in 55 the coils 23 and 24; that all of the magnetic lines inclosing the electric conductors of the primary circuit, pass either through the generator coils 7 and 8 or through the transformer core 25, that the electromotive force 60 wave is of the form shown by the curve in Fig. 6, that the flux through the coils 7 and 8 is a minimum, and the flux in the transformer core 25 is zero when the inductor 12 is horizontal.

65 With the switches 43, 44, 45 and 51 open,

as before referred to, so that the secondaries of both transformers and the primary of one of the transformers is open so that only the primary consisting of the coils 23 and 24 is in circuit, if the rotor 70 12 be rotated clockwise, starting from the horizontal, the flux through the coils 7 and 8 will increase until the inductor reaches its vertical position. This increase of flux will induce a positive electromotive 75 force in the generator coils 7 and 8 and force a positive current through the primary 23 and 24. This will induce a positive flux through the transformer core 25, which will in turn induce a negative reactive electromotive force in the transformer primary coils. The total variation of the generator flux must be sufficient to supply electromotive force to overcome the reactive electromotive force in the transformer primary and also to force the current through the resistance of the primary circuit. The total increase of the generator flux therefore, exceeds the total increase of the transformer flux by an amount sufficient 80 to force this magnetizing current through the resistance referred to. Therefore, when the inductor 12 reaches its vertical position, the generator flux will be a maximum, and also the transformer flux will be a maximum, 85 the generator flux equaling the transformer flux plus an amount which the generator flux exceeds the transformer flux, which amount is occasioned by the excess variation of generator flux, as before referred to, 90 which is necessary to force the magnetizing current through the ohmic resistance of the primary circuit, the value of the transformer flux being represented by P in Fig. 2.

As the generator inductor 12 rotates from 95 the vertical, the generator flux decreases. This causes a negative electromotive force to be induced in the generator coils 7 and 8. The transformer flux also decreases. As the transformer flux decreases, it induces a positive reactive electromotive force in the transformer primary coils 23 and 24 and during the interval that the transformer flux is decreasing from the maximum P to residual magnetism Q (Fig. 2), the decrease of the 100 transformer magnetism exceeds the decrease of the generator magnetism by an amount such that the reactive electromotive force of the primary coils exceeds that of the generator to such an extent as to force the magnetizing current through the ohmic resistance of the primary circuit. Therefore, when the transformer magnetism has decreased to its residual value, the generator flux will exceed the transformer flux by a 105 certain amount which is occasioned by its greater rate of increase during its rise and its less rate of decrease during its fall.

During the interval that the transformer flux is decreasing from the maximum re- 110

sidual magnetism at Q (Fig. 2) to zero at R, the decrease of the generator flux exceeds the decrease of the transformer flux by a variation sufficient to produce an electromotive force adequate to force the magnetizing current through the ohmic resistance of the primary circuit. Therefore, when the transformer flux has decreased to zero, the relation of the generator flux to the transformer flux is that the generator flux is equal to the transformer flux plus the amount which the generator flux exceeds the transformer flux at point Q of the curve in Fig. 2, as above referred to, minus the flux due to the excessive decrease of the generator flux over the decrease of the transformer. If, therefore, X represents the generator flux, Y, the transformer flux, Z the amount by which the generator flux exceeds the transformer flux at point P, W the amount of flux by which the generator flux exceeds the transformer flux by reason of the greater decrease of the transformer flux from the point P to the point Q in Fig. 2 and V the amount of flux difference between the generator flux and the transformer flux due to the difference of decrease of these fluxes between the points Q and R of the magnetization curve in Fig. 2, then the relation of the fluxes is shown by the equation $X = Y + Z + W - V$, but at the point R, Y is equal to 0; consequently at this point the generator flux is shown by the equation, $X = Z + W - V$. $Z + W - V$, however, is the amount of flux due to flux variations to produce electromotive forces for overcoming the ohmic losses of the primary circuit and may be represented as a whole by the character t . It thus appears that there is still some generator flux at the time that the transformer flux is zero. While this remaining flux in the generator is decreasing to zero, as the inductor 12 moves into its horizontal position, the flux variation starts the reversal of the magnetic polarity of the transformer flux and produces the line R-S below the horizontal axis H. As the generator inductor again turns from the horizontal, the generator flux increases as before and the transformer flux rises along the dotted line to a point p which is below the point p in Fig. 2. As the generator flux again decreases to zero (the inductor turning from the vertical to the horizontal), the transformer flux decreases to zero and with a reverse polarity to a point S-S below the horizontal axis, the maximum value p being less than the maximum P. So with each successive cycle the maximum value of the positive transformer flux decreases and the value of the negative maximum transformer flux increases until the transformer magnetism alternates with the positive and negative maximums equal in amount as shown in Fig. 4, when the values of Z, W and V above

referred to, which are the amounts of flux corresponding to variations required to produce electromotive forces to overcome the ohmic losses in the primary circuit during the positive portion of the magnetization curve, are respectively equal in amount to the corresponding flux quantities during the negative portion of the magnetization. Therefore, when the maximum negative transformer magnetism is equal in amount to the maximum positive transformer magnetism, there is no further change in the relation of these maximums, and the algebraic sum of the flux variations required to overcome ohmic losses as referred to above, is zero. Since the generator flux which exists when the transformer flux has decreased to zero, (this being the inherent force causing the change in the relation of the maximum positive and negative transformer fluxes) is equal in amount to the excess of the flux variations required to overcome ohmic losses of the positive current over the flux variations required to overcome ohmic losses of the negative current, then if the algebraic sum of the flux variations required to overcome these ohmic losses were reduced to zero, the generator flux existing at the time of zero transformer flux, would also be zero. The relation of the generator flux to the transformer flux would then be the same at the end as at the beginning of the cycle, each successive cycle would begin and end with the same relation of generator flux to transformer flux and of positive and negative transformer fluxes. Consequently the transformer flux would be a varying flux of one magnetic polarity only, following the general curve of the solid line in Fig. 2. So long, however, as the algebraic sum of the flux variations required to overcome the ohmic losses does not equal zero, the transformer flux will have a value at the end of the cycle, different from the value at the beginning of the cycle. Consequently the relation of the positive and negative maximum transformer fluxes will change with each successive cycle until there exists such relation of this maximum that the algebraic sum of the flux variation required to overcome the ohmic losses is zero. Conversely, if the relation of the maximum positive and negative transformer fluxes remains unchanged during a succession of cycles, then must the algebraic sum of the fluxes required to overcome ohmic losses, be zero. In the foregoing discussion, it has been assumed that a circuit has been completed only through the primary consisting of the coils 23 and 24, across the terminals 9 and 10 of the generator. If, now, the switches 45 and 51 are closed, the secondary circuit of the transformer will be closed through the secondary coils 31 and 32, and the resist- 130

ances 39 and 40. It has already been seen that the portion of the resistance 40, included in the secondary circuit, is adapted to be short circuited at certain portions of 5 the revolutions of the inductor 12 of the generator, this short circuit taking place through the brushes 20 and 21 and the ring segments upon which they bear. These segments are so arranged and connected and 10 the brushes mentioned so placed upon them, that the shunt about the resistance 40 will be open, and consequently the resistance 40 inserted in the secondary circuit, while the inductor is rotating from the horizontal to 15 vertical. During the interval that the inductor is rotating from the vertical, the shunt path through the brushes about the resistance 40 is closed so that this resistance is cut out of the secondary circuit. If it be 20 assumed that the secondary current which flows when the inductor is rotating from the horizontal to the vertical is positive, and that the secondary current which flows when the inductor is rotating from the vertical to 25 the horizontal, is negative, it will be apparent that the negative secondary current will exceed the positive secondary current by an amount depending upon the value of the resistance 40. The excess of negative 30 secondary current will be supplied by an excess of negative primary current which will cause an excess of negative ohmic losses in the primary circuit and consequently the algebraic sum of the flux variation required 35 to overcome ohmic losses will no longer be zero. Hence there will be an inherent force as before referred to, causing the relation of the positive and negative maximum transformer fluxes to continue to change until 40 said algebraic sum is equal to zero. The amount of said change will depend upon the amount of the excess negative current referred to, which in turn depends upon the value of the resistance 40. If the resistance 45 40 be adjusted to such a value that the excess of negative current will cause an additional flux variation of minus t , where t equals $Z + W - V$, to overcome ohmic losses in the primary circuit, then the relation of the 50 positive and negative maximum transformer fluxes will continue to change until the transformer flux is a varying flux of one magnetic polarity only, giving a curve of the general form of the solid line of Fig. 55 2. If the resistance 40 be adjusted to an amount less than that required to produce the flux variation t , the transformer flux will be an alternating flux with the maximum polarity of different signs unequal, 60 giving a curve of the general form of Fig. 3. If 40 be adjusted to an amount greater than that producing the flux variation t , then the transformer flux will be a varying flux of one polarity only, but not decreasing to zero, and giving a curve of the

final form as in Fig. 5. Where the alternating transformer flux is of equal positive and negative maximum values as in Fig. 4, the positive magnetizing current equals the negative magnetizing current, while with 70 the transformer flux of unequal positive and negative maximums, as in Fig. 3, or a flux of one polarity only, as in Figs. 2 or 5, the positive magnetizing current exceeds the negative magnetizing current in the primary circuit, but in each instance, the negative load current in the primary circuit required to supply the negative load current in the secondary is sufficiently in 75 excess of the positive load current in the primary circuit required to supply the positive current in the secondary circuit, that the combined load and magnetizing negative currents in the primary circuit 80 is equal to the combined load and magnetizing positive currents in the primary circuit. Therefore a periodic unbalance of the secondary current will not cause an unbalance of the total current in the primary circuit, except during the interval of 85 the succession of cycles when the relation of the positive and negative maximums of transformer magnetism is changing to cause such unbalance of the magnetizing current as will neutralize the unbalance of 90 the load current.

A further explanation is that the increase of the transformer flux is opposed by the secondary current, also the decrease of the transformer flux is opposed by the secondary current. The amount of opposition depends upon the amount of secondary current, hence by increasing the secondary current during the interval of the negative (demagnetizing) current in the primary circuit, the secondary opposition to the demagnetizing of the transformer core exceeds the secondary opposition to the magnetizing of 100 said core.

If the switch arm 47 be moved from engagement with the contact 49 into engagement with the contact 48, the short circuiting shunt for the resistance 40 will be formed through the brushes 21 and 22 instead of through the brushes 20 and 21 as previously 110 noted. The brush 22 is placed substantially 90° removed from the brush 20 so that the shunt will be closed and the resistance 40 removed from the secondary circuit when the inductor 12 is moving from the horizontal to the vertical and hence there will be an excess of positive secondary current during this interval. This operates to reverse the polarity of the transformer flux, which is necessary in order to cause an excess negative magnetizing current to neutralize the excess positive load current, thereby balancing the total current in the primary circuit. It should be noted that this reversal is made 115 without in any way altering the connection 120

of the generator to the primary magnetizing coil of the transformer and with only an instantaneous unbalancing of the total current in the primary circuit.

5 With all switches closed as shown in Fig. 1, the transformer cores 25 and 36 will be magnetized so that the flux in the core 25 will be a maximum when the flux in the core 36 is a minimum. The connection of the 10 generator terminals to the primary coils 23 and 24, is the same as the connection to the primary coil 35. The core fluxes are, however, in quadrature and differ in magnetic polarity, because the secondary coils 31 and 15 32 have the resistance 40 in their secondary circuit, short circuited during the interval of negative current, while the secondary coils 37 and 38 have the resistance 42 in their secondary circuit short circuited during the 20 interval of positive current.

In the diagram of Fig. 8, the generator is arranged as shown in Fig. 1, and the transformer primaries 23 and 24 are adapted to be connected across the generator terminals 25 9 and 10. The elements of the generator and the transformer are the same as the construction illustrated in Fig. 1 and the same reference numerals have been applied thereto. There is, however, a switch 74 inserted in 30 the primary circuit. The secondary circuit of the transformer including the secondary coils 31 and 32, is, however, modified so that in addition to including the resistances 39 and 40, it also includes a transformer having 35 the primary windings 72 and 73 connected in series with the resistances 39 and 40 in the circuit of the secondary coils 31 and 32. A switch 76 is inserted in this circuit. The primary windings 72 and 73 are wound on a 40 magnetic core consisting of the ring 71 providing a closed magnetic circuit, and also the open ring 68 having the poles or ends 69 and 70. Wound upon this core is a short circuited secondary coil 145. The apparatus 45 of Fig. 8 is also provided with switching mechanism comprising the stationary contacts 48 and 49, and the movable contact 50 secured to the pivoted switch arm 47. Except as above stated, the connections are the 50 same as those described in Fig. 1 and the same reference numerals have been used for like parts in the two figures.

With the switches set as shown in Fig. 8, if the inductor rotor 12 be rotated in a clockwise direction, let it be assumed that the 55 path of the primary current through the coils 23 and 24 will be from the terminal 9 through the conductor 77, switch 74, coils 23 and 24, and conductors 78 and 79, to the 60 other terminal 10 of the generator. During the positive half cycle, the path of the secondary current will be from one terminal of the winding 31 through the resistance 39, conductor 84, switch 76, winding 73, winding

72, conductor 83, conductor 85, resistance 40, 65 to a terminal of the secondary winding 32. During the interval of the negative half cycle, the secondary current has a shunt around the resistance 40 as follows: from the conductor 85 through the switch arm 47, contact 49, conductor 81, brush 20, collector segment 15, connector 17, ring 19, brush 21, conductor 80 and switch 75, to the adjustable arm contacting with the resistance 40. If the resistance 40 be adjusted as explained 70 in connection with the apparatus of Fig. 1, the transformer flux in the core 25 may be a varying flux of one magnetic polarity only. The secondary current, however, of this transformer, acts as an unbalanced primary 80 current in the windings 72 and 73 of the transformer having the core 68. The flux in the core 71 and 68, will also be a varying flux of one polarity only. This will appear from the explanation made in connection with the 85 apparatus of Fig. 1, as it was there set forth that the unbalancing of the transformer flux was caused by the reaction on the primary circuit and the unbalancing of the ohmic losses therein.

As explained hereinbefore, the flux in the core 25 is a maximum when the inductor 12 is vertical. The flux, however, is a maximum in the core 68 and 71 when the inductor is horizontal. It should be noted 90 that the only magnetizing current supplied by the generator, is a balanced alternating current supplied to the primary winding 23 and 24. By a periodic variation of the resistance in the secondary circuit, however, where the resistances are different for different polarities, the alternating energy supplied to the primary winding, is so distributed between the windings 23 and 24 and the windings 72 and 73, as to induce 100 a varying flux of one polarity in the core 25 and a varying flux of one polarity in the core comprising the rings 68 and 71, the flux in 25 being in quadrature with the flux in 68 and 71.

The polarity of the flux of the core 25 and also that of the flux of the core 68 and 71 is reversed by moving the reversing switch arm 47 so that the contact 50 engages with the contact 48 instead of the 110 contact 49. It should be noted that this reversal of polarity is made without any change of the connection of the generator terminals to the magnetizing windings.

Referring to Fig. 9, the generator field structure comprising the ring 91 and the pole pieces 89 and 90, are arranged as in the generator of Fig. 1. The exciting coils 87 and 88 are connected in parallel across the exciter generator 86, by a switch 108 120 the poles 89 and 90 being of opposite polarity as is well understood. 92 represents 125 a single phase alternating current winding

on the armature 93 fixed on the rotating shaft 94, the arrangement of such windings being well understood in the art. The ends of the winding 92 are respectively connected to the collector rings 95 and 96, which also turn with the shaft 94 and upon which bear the brushes 101 and 102. These brushes are connected to the terminals of the transformer primary windings 23 and 24 by means of conductors 109 and 111, this primary circuit being controlled by means of the switch 107. The core of this transformer is constructed in the manner as described in connection with the apparatus of Fig. 1, the core 25 of magnetic material having at its poles 26 and 27 a body 30 of magnetic material which is supported by means of the non-magnetic studs 28 and 29 and is spaced from the ends of the core 25 by means of non-magnetic washers 33 and 34. The secondary coils 31 and 32 have their circuit completed through the non-inductive resistance 39, the conductor 115 and the adjustable resistance 40. Provision is made for short circuiting the resistance 40 periodically in synchronism with the rotation of the generator armature. This short circuiting is effected by means of the conductor 112 which connects with one terminal of the resistance 40 through the switch 106, the conductor 112 being connected with the brush 103 bearing upon the collector ring 97, which is connected by the low resistance connection 98 with the collector ring segment 99. Completing the circle of the segment 99, but insulated therefrom is the segment 100. Adapted to bear upon the segments 99 and 100, are the brushes 104 and 105 which are respectively connected by conductors 113 and 110 with the stationary contacts 48 and 49 of the switch, having the movable contact 50 adapted to be moved alternately into engagement with the stationary contacts 48 and 49 by the pivoted switch arm 47, which is connected by the conductor 114 with the other terminal of the resistance 40. With the switch in the position shown, that is with the contact 50 in engagement with the contact 49, the resistance will be short circuited by the connection 98 whenever the brush 105 is upon the segment 99. It will be understood that the collector rings 95, 96, 97 and the collector ring segments 99 and 100 are fixed to and rotate with the shaft 94. When the switch arm 47 is thrown into its other position, namely with the contact 50 into engagement with the contact 48, the resistance 40 will be short circuited by the connector 98 whenever the brush 104 is upon the segment 99. In the first instance, that is with the switch as shown in the drawing, the short circuit about the resistance 40 is open whenever

the brush 105 is upon the segment 100, and when the switch is thrown to its other extreme the short circuit is open when the brush 104 is upon the segment 100. It will be seen that with a two pole generator as shown, the brushes 104 and 105 are located substantially 180° apart, while the segment 100 occupies somewhat less and the segment 99 somewhat more than one-half of a circumference.

With all the switches set as shown in Fig. 75, if the armature 93 be rotated clockwise, the path of the current is from the collector ring 96 through brush 101, conductor 109, switch 107, transformer primary coils 23 and 24 and conductor 111 to the brush 102 on the other collector ring 95. During the interval of positive current, the path of the secondary current is from one terminal of the coil 31 through resistance 39, conductor 115 and resistance 40 to the coil 32. During the interval of negative current, the secondary has a shunt around the resistance 40, as before described, thereby causing an excess of negative secondary current magnetizing the core 25. By adjusting the resistance 40 as explained in connection with the apparatus of Fig. 1, the flux in the core 25 may be unbalanced or even have but one polarity only. If the switch be moved so that the contact 50 comes into engagement with the contact 48, the shunt around the synchronous resistance will be effected through the brush 104, as before referred to, thereby causing an excess of positive secondary current acting to magnetize the core 25.

In Fig. 10 instead of having the collector rings controlling the short circuit around the resistance 40, secured to the generator so as to rotate therewith, these rings are rotated by means of a synchronous motor. 105 Thus a polyphase alternating current generator 116 supplies a transformer 117 which may be a step up transformer for adapting the current for transmission. After such transmission, the voltage may be stepped down, by a transformer 118. From one phase of this transformer, current is supplied through the conductors 127 and 128 to the transformer primary 133, having a core comprising the continuous ring of magnetic material 137 and the open ring 136. Upon this core are mounted the secondary windings 134 and 135 which have their circuit completed through the non-inductive resistance 39 and the adjustable resistance 40. 110 The resistance 40 is adapted to be short circuited by means of conductors 126 and 132 connected with its terminals and which at their other ends are connected with the brushes 124 and 125. The former is adapted to bear upon the separated segments 122 and 123, while the brush 125 bears upon the continuous ring 120. The ring 120 is con-

ected with the segment 122 by means of a low resistance connection 121, so that when the brush 124 rests upon the segment 122 it will be connected by low resistance connection with the brush 125 and thus form a short circuit about the resistance 40. When the brush 124 is upon the segment 123, the short circuit is open and the resistance 40 in the secondary circuit. The collector ring 10 and segments just referred to are rotated by means of a synchronous motor 119 which is fed through the conductors 129 and 130 connected respectively to the conductors 127 and 128 and also through the conductor 131 15 which is connected to the other terminal of the secondary of the transformer. The motor 119 will therefore rotate in synchronism with the generator 116 so that the effect upon the transformer secondary circuit will 20 be the same as if the collector rings were mounted upon the shaft of the generator as hereinbefore referred to, and the flux in the core of the transformer having the primary 133, may be unbalanced between the two 25 polarities or have a single polarity only by adjusting the resistance 40 as has been before explained.

Referring now to Fig. 11, the generator comprises poles 5 and 6, induced windings 7 30 and 8 and inductor 12 mounted on the shaft 11, collector segments and ring 13 to 16 inclusive and brushes 21 and 22 bearing thereon as described in connection with Fig. 1. Also the apparatus of Fig. 11 has a transformer comprising a core 25 having primary coils 23 and 24 thereon connected across the terminals 9 and 10 of the generator and having secondary windings 31 and 32 connected to the brushes 21 and 22 by 35 means of the conductors 141 and 142 and the switch 144 in conductor 141, all as described in connection with the apparatus of Fig. 1. The primary transformer circuit is controlled by a switch 143 while the secondary circuit is controlled by switch 144, but instead of having a resistance 40 external to the generator structure as in Fig. 1, in the present case the resistances 138 and 139 are connected on the one hand between the 40 segments 14 and 15 and on the other hand between the segments 13 and 16. It will be apparent from observation of Fig. 11 that when the brush 22 is in contact with either the segment 15 or 16, the secondary circuit 45 of the transformer will be closed through either the connection 17 or the connection 18. When, however, the brush 22 is upon either of the segments 13 or 14, the resistance 139 or 138 will be inserted in the secondary 50 circuit. The effect of this periodic insertion of resistance has been before explained. The collector ring segments 13 to 55 15 inclusive, may be formed after the manner of a commutator, that is by conducting

bars separated by insulating pieces. As illustrated in the fragmentary view of Fig. 12, the segments 14 and 15 are shown as separated by a block of insulation with the resistance 138 spanning the insulation and connecting the segments 14 and 15 together. 65 70

For the purpose of simplifying, it has been assumed in connection with foregoing explanations, that the sum of the turns of the generator windings 7 and 8 is equal to the sum of the turns of the transformer 75 primary windings 23 and 24. It will be understood, however, that the operation of the invention is not dependent upon any exact relation between these turns. It was also assumed for purposes of explanation 80 that the electromotive force curve was of the form shown in Fig. 6, but the operation of this invention does not depend upon any particular form of curve. Also the explanations assume that all of magnetic lines 85 enclosing conductors of the primary circuit pass either through the generator coils 7 and 8 or through the transformer core 25, but it has been explained that if the transformer flux continues through a succession 90 of cycles with any degree of inequality between maximum positive and maximum negative, the addition of line inductance to the primary circuit will not destroy this 95 relationship (as the algebraic sum of flux variations due to line inductance when taken after an entire cycle, is zero) providing the brushes have sufficient lead so that the increase of the primary circuit is during the 100 interval of the proper half cycle of the primary current. It is important for economical operation, that during the entire interval of negative (or demagnetizing) primary current, there shall be a synchronous decrease of the secondary circuit, thereby allowing a sufficient secondary current to prevent the reversal of polarity of the primary current. This is especially important when the magnetic circuit is open 105 (see non-magnetic washers 33 and 34) as a very little primary demagnetizing energy will reverse the flux in 25, unless said demagnetizing energy is opposed by a secondary current which absorbs the greater 110 part of said demagnetizing energy. The best results have been obtained by so proportioning the slip ring segments, that the 115 interval of synchronous decrease of the secondary circuit is greater than one-half cycle. This avoids the necessity of determining the exact neutral position of the brushes. 120

In the arrangement of Fig. 8, the inclusion of the reactance of the primary coils 72 and 73 in the secondary circuit of the transformer having the core 25, interferes to some extent with the secondary current which opposes the demagnetizing of the core 125

25 so that a larger adjustment of the resistance 40 is required than would be the case if the coils 72 and 73 were not in the secondary circuit.

5 What I claim is—

1. A means for exciting by an alternating current, magnetic flux of which flux of one polarity predominates over the flux of the other polarity, comprising in combination 10 an exciting winding for producing flux, means for applying alternating current to said winding, a secondary winding in inductive relation to said primary winding and means for increasing the ohmic resistance 15 of the circuit of said secondary winding during one alternation of current over the ohmic resistance of said secondary circuit during the next preceding current alternation.
- 20 2. The method of producing an asymmetric alternating flux from a source of symmetrical alternating E. M. F. in an apparatus comprising a magnetic core, a primary winding thereon supplied from said 25 source, a second winding thereon in inductive relation to said primary winding, and an impedance in the circuit of said secondary winding, which comprises cyclicly varying the value of said impedance synchronously with the E. M. F. of said source.

3. The method of producing an asymmetric alternating flux from a source of symmetrical alternating E. M. F. in an apparatus comprising a magnetic core, a primary winding thereon supplied from said 35 source, a second winding thereon in inductive relation to said primary winding, and an impedance in the circuit of said second winding, which comprises controlling the

magnetomotive force of said second winding so as to produce unequal reactive effect during successive half cycles of the source of E. M. F.

4. The method of producing a unidirectional pulsating flux from a source of symmetrical alternating E. M. F. in an apparatus comprising a magnetic core, a primary winding thereon supplied from said source, a second winding thereon in inductive relation to said primary winding, and an impedance in the circuit of said second winding, which comprises controlling the magnetomotive force of said second winding so as to produce unequal reactive effect during successive half cycles of the source of E. M. F.

5. The method of producing a unidirectional pulsating flux and the method of reversing the magnetic polarity of said flux from a source of alternating E. M. F. in an apparatus comprising a magnetic core, a primary winding thereon supplied from said source, a second winding thereon in inductive relation to said primary winding, and an impedance in the circuit of said second winding which comprises controlling the magnetomotive force of said second winding so as to cause the reactive effect during the half cycles of one sign of a succession of cycles of E. M. F. to be in excess of the reactive effect of the half cycles of the opposite sign of E. M. F. and the changing of said excess reactive effect to the half cycles of the opposite sign.
